US00D947579S

(12) **United States Design Patent** (10) **Patent No.:** **US D947,579 S**
Chen (45) **Date of Patent:** **** Apr. 5, 2022**

(54) **ELECTRIC LIFT TABLE**

(71) Applicant: **zhejiang zhongwei smart furniture Co., LTD**, Zhejiang (CN)

(72) Inventor: **Qiankui Chen**, Hunan (CN)

(73) Assignee: **Zhejiang Zhongwei Smart Furniture Co., LTD**, Yueqing (CN)

(**) Term: **15 Years**

(21) Appl. No.: **29/741,854**

(22) Filed: **Jul. 16, 2020**

(30) **Foreign Application Priority Data**

Jun. 15, 2020 (CN) 202030304355.6

(57) **CLAIM**

The ornamental design for an electric lift table, as shown and described.

DESCRIPTION

FIG. 1 is a perspective view of an electric lift table showing my new design;

FIG. 2 is a front view thereof; with the rear view being a mirror image thereof;

FIG. 3 is a left side view thereof; with the right side view being a mirror image thereof;

FIG. 4 is a top plan view thereof;

FIG. 5 is an enlarged view of portion "5" shown in FIG. 2; and,

FIG. 6 is an enlarged view of portion "6" shown in FIG. 3. The broken lines depict portions of the article that form no part of the claimed design.

1 Claim, 6 Drawing Sheets
